UNITED STATES PATENT OFFICE.

JOHN R. PEIRCE, 3D, AND GEORGE MASON ANDREWS, 2D, OF PHOENIXVILLE,
PENNSYLVANIA.

DESIGN FOR A FLOWER SCONCE OR SIMILAR ARTICLE.

Application filed August 23, 1926. Serial No. 18,812. Term of patent 3½ years.

To all whom it may concern:

Be it known that we, JOHN R. PEIRCE, 3d, and GEORGE MASON ANDREWS, 2d, both citizens of the United States of America, and residents of Phoenixville, in the county of Chester and State of Pennsylvania, have invented a new, original, and ornamental Design for a Flower Sconce or Similar Article, of which the following is a specification, ref-

erence being had to the accompanying drawings, forming a part thereof.

The figure is a perspective view of a flower sconce showing our new design.

We claim:—

The ornamental design for a flower sconce or similar article, as shown.

JOHN R. PEIRCE, 3RD.

GEORGE MASON ANDREWS, 2D.
